UNITED STATES PATENT OFFICE

2,514,401

LAND MINE

Lyle K. Liljegren, Silver Spring, Md., assignor to
the United States of America as represented by
the Secretary of War

Application August 17, 1942, Serial No. 455,040

11 Claims. (Cl. 102—8)

(Granted under the act of March 3, 1883, as
amended April 30, 1928; 370 O. G. 757)

1

The invention described herein may be manufactured and used by or for the Government for governmental purposes, without the payment to me of any royalty thereon.

The invention relates to a land mine and more particularly to such a mine adapted for use against tanks and other vehicles and is of a type to be actuated only by masses greater than a predetermined limiting value to avoid the possibility of accidental detonation by foot troops.

It is an object of this invention to provide a land mine which will only detonate in response to engagement with a mass above an accurately predetermined and maintainable ceiling level.

It is a further object to provide a land mine which may be constructed of a material which will be proof against detection by magnetic or inductive means.

Additional objects are the provision of a mine which may be economically constructed of non-critical material and which permits of considerable saving in weight of materiel.

The specific nature of the invention as well as other objects and advantages thereof will clearly appear from a description of a preferred embodiment as shown in the accompanying drawings in which:

Fig. 1 is an axial sectional view of my improved mine, and

Fig. 2 is a top plan view of the same.

Fig. 3 is a partial axial sectional view in the same plane as Fig. 1, the spider plug being shown in safe condition.

Referring to the drawing by characters of reference, the mine shown therein comprises a generally cylindrical body 1 which is externally threaded for the reception of a centrally apertured cap member 2. A spider 3 is supported above the cover and provided centrally with an adjustable spider plug 4. A plurality of resilient spider supports 5 are engaged between the spider 3 and the cover 2.

The mine body 1 is filled with a suitable high explosive 6, such as TNT, and a fuze well cup 7 is supported from the central aperture in the cover 2. Seated in the fuze well cup 7 is the fuze comprising a booster charge 8, which may be of tetryl, and a percussion primer 9. A firing pin 10 is supported in alignment with the primer 9 and a compression cylinder 11 of rubber or other non-metallic spring material is engaged between the firing pin 10 and a trigger button 12. It should be noted that the trigger button has capacity for axial sliding movement in the fuze body 13 of about $\frac{1}{4}$ " at the close of which the lower end of

2

the trigger button engages the retaining flange 14 on the firing pin 10. It is obvious that the application of any greater than a certain critical load to the trigger button will result in destruction of the flange 14 and that the compressed cylinder 11 will thereupon drive the firing pin into the primer detonator 9.

The spider 3 as is usual in such devices is provided with downwardly extending legs 15 adapted to hook under the rim of the cover 2 and locating projections 16 are preferably provided on the edge of the cover 2 to insure against rotatory movement of the spider with respect to the cover. In my improved mine, however, the entire resistance to a load on the spider need not be supplied by the trigger button 12 as in the conventional construction. I have, instead, provided at spaced intervals on the periphery spider supports 5 of rubber or material of similar elasticity through which thrust loads received on the spider may be transferred directly through the compressible supports to the body 1 and then passed on to the ground. As such forces are absorbed at or near the point of application I am enabled to make my spider of material having considerably less strength and rigidity than that conventionally used. At the same time the use of spaced resisting elements about the periphery of the body takes from the fuze the requirement of containing a spring sufficiently stiff to resist the entire actuating load and enables the trigger button of the fuze to function solely as a device to actuate the mine whenever a predetermined movement of the spider is exceeded thus improving the accuracy with which the trigger action may be controlled.

The dimensions and compressive ratios of the spider supports can be adjusted to permit the spider to operate the trigger through its preliminary or safety movement at any desired load value, but it is believed to be preferable to make that load about 500# to insure that the mine will not be detonated by being stepped on by a man, while it will be sure to operate if run over by any military vehicle. Further adjustments can be made by regulating the position of the spider plug 4. Whenever less than the maximum load is applied the parts will be restored to normal condition upon release of the load. If, however, the maximum load is exceeded the retaining flange 14 will be destroyed, and the mine will detonate, destroying or seriously damaging the attacking vehicle.

For storage in assembled condition with maximum safety it will be noted that the spider plug

4 is provided with a central recess 17 which, when the plug 4 is reversed as shown in Fig. 3, fits over the trigger button 12. In this way the spider can be forced completely against the mine body without moving the trigger button through a sufficient distance to actuate the fuze. Recesses 18 are provided in opposite faces of the spider plug and near its rim to enable it to be readily screwed in or out for reversing or adjusting the plug.

Thus far in the specification little reference has been made to the choice of material for my improved mine. It should be realized that my construction will permit more economical manufacture with usual materials because less strength will be needed in the spider and other critical members. A more important effect of my improved design is that by permitting the parts to be of less strength, a far greater field of materials is opened up for selection. Thus it is that my mine may be made of non-magnetic and/or non-metallic material which will be undetectable by the magnetic or inductive means employed to search the ground for hidden metallic bodies. A wide variety of modern plastic materials fully meet the requirements of this service and present the further important advantages of allowing reduction in weight and avoiding the use of critical strategic materials.

I claim:

1. A land mine comprising an explosive containing body, a trigger button projecting from the upper face of said body, a spider spaced from the upper face of said body, and a spider plug reversibly mounted in said spider in alignment with said trigger button, said spider plug having formed on one face thereof a trigger button engaging member and on the opposite face thereof a recess adapted to receive said trigger button when said plug is reversed in said spider.

2. A land mine comprising an explosive containing body, a trigger button projecting from the upper face of said body and adapted to actuate the mine upon being forced into said body, a spider member resiliently supported in spaced relation to the upper face of said body, a threaded aperture in said spider member in alignment with said trigger button, and a spider plug adapted to be secured in said aperture, said spider plug being formed with a recess in one face adapted to receive the trigger button when said spider plug is inserted in said spider with the recess facing downwardly, and a trigger engaging member formed on the opposite face of said plug in axial alignment with said recess.

3. A land mine comprising a substantially cylindrical explosive containing body, having a downwardly facing rim, a fuze in said body, a trigger button projecting from the upper surface of said body, a spider spaced above said body having an annular rim and having a portion in alignment with said trigger button, resilient spider supports about the periphery of said body engaged between said body and said rim, and spaced depending legs on the annular rim of said spider having hook members engaged beneath said downwardly facing rim.

4. A land mine as described in claim 3, all of the parts of said mine being made of non-metallic material.

5. A land mine comprising a substantially cylindrical body, an explosive charge in said body, a centrally apertured cover on said body provided with a downwardly facing rim at the periphery of said body, a fuze in said body having a trigger

button projecting through said centrally apertured cover, a spider having a central trigger engaging member and an annular rim of substantially the same diameter as said body, spaced depending legs on said spider, inturned hooks on said legs engaged beneath said downwardly facing rim, and a plurality of spaced, resilient spider supports engaged between said cover and said annular rim to support said spider in spaced relation above said body.

6. A land mine as described in claim 5, all of the parts of said mine being made of non-metallic material.

7. In a pressure-detected mine, a body adapted to contain an explosive charge, a fuse carried by said body and including a trigger button projecting therefrom and movable downwardly to detonate said fuse, a pressure plate superposed over said button and connected with said body for translation toward said body, and a reversible and removable insert secured to said pressure plate over said button, said insert being dished so that in one position it engages said button and operates the same on translation of said plate, while in a reversed position it clears said button for all positions of downward translation of said plate and insert.

8. A land mine comprising a closed non-metallic casing adapted to contain a charge of explosive, and including a cover having a central opening therethrough, a fuze body secured in said opening and extending into said casing, said body having a centrally apertured top wall, a firing pin, frangible means rigidly mounting said pin in and with respect to said casing, a firing button slidably mounted through the aperture in said top wall and having a lower rim engageable with said frangible flange means when said button is depressed from a first to a second position, to thereby break said frangible means and force said pin downwardly into firing position, and non-metallic resilient means interposed between said button and said firing pin to yieldingly hold said button in first position.

9. A land mine as in claim 8, said cover having a generally flat top surface, a spider, means carried by said casing and mounting said spider on and over said casing for sliding movement toward said cover, said spider having a central plug to engage and move said button downwardly to second position and a plurality of non-metallic resilient supports interposed between the rim of said flat cover and said spider to thereby yieldingly hold said spider in spaced relation from said cover.

10. A fuze for a land mine comprising a fuze body, a percussion primer supported therein, a firing pin in alignment with said primer and spaced therefrom, means including a frangible annular web integrally and rigidly uniting said firing pin and said fuze body, a trigger button mounted in said fuze body spaced from said firing pin and with capacity for sliding movement toward said firing pin, said button comprising an annular depending skirt portion to engage and break said frangible web when said skirt portion has been depressed into engagement with the annular web of said firing pin, and spring means confined between said trigger button and said firing pin to yieldingly resist movement of said button into detonating engagement with said firing pin and frangible web.

11. A fuze for a land mine comprising a fuze body, a percussion primer supported therein, a firing pin in alignment with said primer and

spaced therefrom, means including a frangible annular web integrally and rigidly uniting said firing pin and said fuze body, a trigger button mounted in said fuze body spaced from said firing pin and with capacity for sliding movement toward said firing pin, said button comprising a depending portion to engage and break said frangible web when said trigger button has been moved a predetermined distance toward said firing pin, and a body of non-metallic rubber-like material confined between said trigger button and said firing pin to yieldingly resist movement of said depending portion into engagement with said frangible web.
